[57] CLAIM

The ornamental design for a compact disc and book package, as shown and described.

DESCRIPTION

FIG. 1 is a front elevational view of a compact disc and book package showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is an exploded perspective view thereof; and,

FIG. 8 is an exploded perspective view of FIG. 7, the broken line showing of book and compact disk is for illustrative purposes only and forms no part of the claimed design.
